UNITED STATES PATENT OFFICE.

EDWARD ECKL, OF LOS ANGELES, CALIFORNIA

REFRIGERATOR.

Application filed March 6, 1922. Serial No. 541,574.

To all whom it may concern:

Be it known that I, EDWARD ECKL, a citizen of the United States, residing at Los Angeles, in the county of Los Angeles and State of California, have invented new and useful Improvements in Refrigerators, of which the following is a specification.

My invention relates to refrigerators of the type generally used for household purposes, the principal objects of my invention being to generally improve upon and simplify the construction of the existing forms of household refrigerators, to provide simple and convenient means for taking care of the water resulting from the melting of the ice stored within the ice chamber of the refrigerator, to provide for a free circulation of air from the storage chambers of the refrigerator through the ice chamber and further, to provide a refrigerator that may be easily and cheaply produced.

Other objects and advantages will hereinafter appear and while I have shown and will describe my preferred form of construction, I wish it to be understood that I do not limit myself to such preferred form, for various changes and adaptations may be made therein without departing from the spirit of my invention as hereinafter claimed.

In the drawings, Fig. 1 is a perspective view of a refrigerator of my improved construction.

Fig. 2 is a vertical section taken on the line 2—2 of Fig. 1.

Fig. 3 is a horizontal section taken on the line 3—3 of Fig. 2.

Fig. 4 is a perspective view of a drip pan supporting bracket that is utilized in my improved refrigerator.

Fig. 5 is a vertical section taken through the end of the drip discharge spout.

Referring by numerals to the accompanying drawings 10 designates the body of the refrigerator, said body being composed of side, front, rear and bottom walls, all of which are preferably lined with sheet metal 11. The top of the body of the refrigerator is closed by a hinged lid or cover 12, and 50 that portion of the space within the refrigerator body immediately below said lid constitutes an ice chamber 13.

Extending inwardly from the walls of the body 10 at the bottom of chamber 13 are 55 downwardly inclined drip flanges 14 of metal and removably arranged on said

flanges is a rack 15, preferably of heavy wire screen that serves as a support for the ice that is stored in chamber 13.

Secured to the walls of the body 10 immediately beneath the flanges 14 are blocks or brackets 16, preferably of wood, and which are notched as designated by 17 to receive the edges of a shallow drip pan 18.

Depending from this pan near one end is 65 an outlet tube 19 that discharges directly into the upper end of a drain tube 20, and the latter leading through the side wall of the refrigerator body. Pivotaly mounted near the outer end of drain tube 20 is an 70 outwardly opening gravity closed valve 21, that is designed to act automatically, and open under the weight of a small amount of water within the drain tube and to close by gravity, thereby preventing air from entering 75 the refrigerator through the drain tube.

Removably suspended on the side of the refrigerator body below the discharge end of the drain tube is a receptacle 22 that receives the water that passes from the refrigerator through said drain tube.

The space within the refrigerator body below the drip pan constitutes a storage chamber for food stuffs and the like and said space may be divided into one or more 85 compartments by removable partitions 23 that are formed of wire screen or perforated sheet metal.

Suitable doors 24 are arranged in the front wall of the refrigerator body which provide 90 access to the storage space beneath the drip pan and permit the drip pan 18 to be introduced into or removed from the refrigerator.

All water dripping from the ice within 95 chamber 13 passes downwardly onto and over drip flanges 14 and from the latter into the pan 18.

From this pan 18 the water discharges through outlet 19 into and through discharge 100 pipe 20 and after passing automatic valve 21 said water discharges into receptacle 22 and which latter may be easily and conveniently removed whenever it becomes necessary to remove the accumulation of waste 105 water.

The blocks or brackets 16 are arranged so as to provide ample space between the edges of the drip pan 18 and the walls of the refrigerator body and consequently permitting 110 a free circulation of air between the ice and food storage chambers.

A refrigerator of my improved construction is comparatively simple, may be easily and cheaply produced, is constructed so as to be readily cleaned and is very effective in performing its intended functions.

I claim as my invention:

In a refrigerator, an ice chamber, a drip flange below said chamber, a door in the

front of the refrigerator, brackets in the refrigerator below said drip flange and a 10 drip pan supported on said brackets, said brackets and door being so arranged that said pan may be passed therethrough to be positioned in the refrigerator or removed therefrom.

EDWARD ECKL.
